UNITED STATES PATENT OFFICE

BASIL NORRIS ABBOTT, OF RICHMOND, VIRGINIA

FLAT-TOP-DESK CABINET

Application filed June 17, 1926. Serial No. 116,693.

The invention relates to new and useful improvements in cabinets, and is more particularly adapted for use with the usual single or double flat-top desk.

One of the objects of my invention is the provision of a cabinet designed to accommodate, in a systematic manner, paraphernalia such as scissors, mending tape, clips, rubber bands, calendars, memorandum sheets and similar articles which are used daily in clerical or business endeavors.

Another object of the invention is the provision of a cabinet adapted to remain in a stationary position on the top of a desk or place and give access to aforesaid paraphernalia.

A still further object of my invention is the provision of a convenient storage place for detachable cabinet doors.

Other objects and features will more fully appear from the following description and accompanying drawings, in which:

Fig. 1 is a sectional view taken along lines 1—1 of Fig. 2; Fig. 2 is a side view taken 25 along lines 2—2 of Fig. 1; Fig. 3 is a top plan view along lines 3—3 of Fig. 2, and Fig. 4 is a sectional side view showing a modification of the invention.

Referring to the drawings, ends 1—1 are secured to a base 2 and top 3, which extends along and is flush with, portions of the inner edges of said ends.

A support 4 having a vertical partition 5 thereon, is secured to said end members, 35 and braces 6 secure said support and also form four small compartments 7 that are adapted to accommodate such articles as tape, inkpads and boxes. Vertical holders 8—9, respectively spaced from each other, are secured to said support and partition, and are adapted to accommodate pens, pencils and the like.

Slotted frames 10—10, having tops considerably broader than the width of such frames, are respectively secured to ends 1—1 and are spaced from said support 4 by blocks 11 thereby providing a place for an article such as a ruler. The frames are adapted to accommodate calendars, memorandum sheets, 50 or such other useful information, and by

duplicating such articles used in said frames they may be perceived from either side by an observer.

A horizontal partition 12 is secured to said ends and adapted to support a detachable receptacle 13 having compartments formed by partitions 14, and a shelf 15 secured thereto, may be used to accommodate such articles as paste or gum jars. A container 16 is secured to said shelf and adapted to accommodate brushes or the like. Brackets 17 are secured to the sides of said receptacle for supporting such articles as pencils and pens. Angular studs 18 may be secured to said partition to prevent horizontal displacement of said receptacle or such articles as inkwells and paste jars. Brackets 19—20, respectively secured to said ends and horizontal partitions are adapted to accommodate pens, pencils or similar articles, while brackets 21—21, respectively secured to said ends may be used to support spool tape or the like, and brackets 22—23, are also secured to said ends for supporting pairs of sissors.

A compartment 24, formed by said base, ends and horizontal partition, accommodates drawers 25 having receptacles 26 formed by partitions 27. The fronts 28—28 of said drawers are of greater height than said partitions but not less than said compartment, and by such an arrangement a small compartment 24' is provided for accommodating detachable doors 30 that enclose each side of said cabinet and rest on said partition and cleats 31—31, 32—32, secured to said ends. A longitudinal strip 27' is secured to partitions 27 at the rear of each drawer and prevents any "creeping" or escape of articles in said receptacles when the drawer is actuated.

Referring to Fig. 5, which is a modification of the invention, a single cabinet may be provided by eliminating all duplicated parts and enclosing the vertical side with a back 36. The door 30 may be set in suitable brackets secured to said back or may be hinged so as to fold and thereby fit in compartment 24'.

It is obvious from the foregoing that when access to the cabinet is desired the detachable

doors need only be removed or drawers opened, and the doors may also be placed in the compartment for convenience, while the cabinet is in use.

- 5 Having described my invention, I claim:
In a cabinet for placement on the top of a flat top desk a partition member which divides the cabinet into an upper and a lower compartment, detachable doors for the upper compartment, drawers for the lower compartment, said drawers having their side walls and rear walls of a less height than their front walls to provide a space for storage of said doors above the top edges of said side and rear walls.
